UNITED STATES PATENT OFFICE.

MARIE KEMPER, OF TOLEDO, OHIO, ASSIGNOR OF ONE-THIRD TO LORENZO RICHARDS AND ONE-THIRD TO ALICE EDWARDS, BOTH OF WASHINGTON, DISTRICT OF COLUMBIA.

SHOE-TIP.

1,355,747.

Specification of Letters Patent.

Patented Oct. 12, 1920.

Application filed April 10, 1919. Serial No. 288,984.

To all whom it may concern:

Be it known that I, MARIE KEMPER, a citizen of the United States, residing at Toledo, in the county of Lucas and State 5 of Ohio, have invented certain new and useful Improvements in Shoe-Tips, of which the following is a specification.

The object of my said invention is to provide a simple and inexpensive metallic guard 10 for the tips of the soles of shoes and one that may be quickly and conveniently attached, whereby this part of the sole ordinarily subjected to unusual wear is protected and the life of the shoe prolonged and its 15 appearance preserved, all as is hereinafter more fully described in the claim.

Referring to the accompanying drawing which is made a part hereof and on which similar reference characters indicate similar parts,

Figure 1 is a view of the toe of a shoe showing my improved protecting clip attached to the point of the sole.

Fig. 2, an under side view of the same, 25 and

Fig. 3, a perspective view with the clip attached.

The shoe, of course, may be any boot or shoe of usual construction, but the clip will 30 ordinarily be more generally used upon ladies' shoes and shoes of comparatively thin soles which are quickly and easily destroyed at the toe by the usual wear.

The clip consists of a metal plate 10 having an overturned front flange 11 adapted to embrace the tip end of the sole with brads 35 12, 13 and 14 formed on the plate and turned up and adapted to project into the sole to secure the clip in place.

40 In attaching the clip the flange 11 is placed over the tip end of the sole and the plate 10 turned toward and against the under side of the sole, as indicated in Fig.

2, and the brads or points 12, 13 and 14 driven into said sole. A metal form is preferably inside the toe of the shoe and the brads being bent forward slightly the driving of the same against the form serves to further bend them forward and to slightly hook or clench them at their inner ends, thus 45 preventing ready detachment.

The clip may thus be readily and quickly attached by anyone and a very inexpensive protection for the toe of the shoe provided and the life of the shoe prolonged and its 55 appearance preserved.

Having thus fully described my said invention, what I claim as new and desire to secure by Letters Patent, is:

A metal tip for protecting the points of 60 the soles of shoes and that portion of the sole immediately adjacent to said point, comprising a thin metal plate adapted to be attached to the sole at the point and formed with attaching brads integral therewith and 65 upturned to penetrate the sole of the shoe, said brads being in-curved slightly and said plate also having a front in-turned flange adapted to embrace the extreme point of the sole and be bent down around the edge of 70 said point, said flange being formed narrow and the body of the plate comparatively wide with the attaching brads spaced apart on said plate, whereby said device is adapted to efficiently protect the tip of the sole, 75 be inconspicuous when in place, and adapted to be quickly and conveniently attached, all substantially as shown and described.

In witness whereof, I have hereunto set my hand and seal at Washington, D. C., 80 this ninth day of April, A. D. nineteen hundred and nineteen.

MARIE KEMPER. [L. S.]
